GAS-FIRED HOT AIR FURNACE

James M. Funk, Rockford, Ill., assignor to Geo. D. Roper Corporation, Rockford, Ill., a corporation of Illinois

Application February 2, 1931, Serial No. 512,803

22 Claims. (Cl. 126—116)

This invention relates to hot air furnaces generally, but has special reference to gas-fired hot air furnaces, and still more particularly one of the so-called hot blast type, that is, one which is arranged to operate with forced draft of the air to be heated instead of relying on natural draft. The principal object of my invention is to design and construct the various portions of the furnace with special reference to forced draft operation with a view to maximum efficiency. For example, to further this object, all heated surfaces are so arranged that they may be easily and completely traversed by the air to be heated, and wherever possible and desirable, the parts are made of streamline form to minimize head resistance and at the same time insure more complete contact of the air with the heated surface. The flues conducting the products of combustion are accordingly streamlined and this gives the important advantage of causing the products of combustion to be spread out into thin streams for the most efficient heat exchange through the walls of these flues with the air coming in contact with the outside thereof. To further insure good efficiency, I provide an air moving apparatus employing an air screw propeller instead of an ordinary rotary fan, and provide in connection with this propeller a specially designed shroud for increasing its air moving efficiency to create the desired draft without excessive power consumption and thus cause the delivery of a large quantity of warm air as against a small volume of hot air produced with a furnace operating with natural draft. This principle of operation accounts for the greatly increased efficiency. As against an efficiency of 60% or even less, which is regarded as the best obtainable with most ordinary gas-fired furnaces with which I am familiar, a furnace made in accordance with my invention has shown an efficiency of better than 90%, which, of course, is sufficient evidence of the soundness of the principle of operation.

The furnace embodies numerous features of novelty, among the more important of which may be enumerated the following:

(1) The arrangement of the cold air inlet and warm air outlet in such relation to the flue system for the counter-flow of air to the products of combustion; the cold air after entry being thereby caused to contact with the coolest flues and the warmest air before leaving being caused to have contact with the hottest flues. This gradual heating of the air in the course of its passage through the furnace casing is conducive toward

higher efficiency and leaves the air in a better condition than is otherwise obtained.

(2) The provision in the flue system of intermediate mixing chambers to tend toward more uniform distribution of the products to the flues in each bank, and a substantially uniform temperature of the products in the different flues of any bank, all of which makes for higher efficiency by reason of uniform heat exchange by all of the flues in each bank.

(3) The provision of one of these mixing chambers with a clean-out hole accessible directly from outside the furnace casing, and the arrangement of banks of flues communicating with said chamber in such a way that the same may be cleaned out readily from outside the casing through the opening mentioned. Incidentally, the banks of flues communicating with said chamber are sloped toward it, and the same is provided with a drain to carry off condensation, so that the chamber serves several purposes, namely, as a mixing chamber, a clean-out, and a condensation trap.

(4) The provision of a separate air jacket for the fire-box discharging to the same outlet with the air circulated over the flue system. A small fan is provided to produce a forced draft through this jacket and is suitably mounted directly on the armature shaft of a motor provided for driving the air screw propeller. A belt connection serves to drive the propeller from the motor at the proper speed reduction. Incidentally, I provide a ship's funnel in the warm air outlet for the discharge of the warm air from the aforesaid jacket into the main stream, said funnel being so disposed that the main air stream impinging thereon creates enough of a reduction in pressure in the funnel to accelerate the flow of air through the jacket. The small fan and the larger air screw propeller are, of course, disposed inside the furnace casing so that the operation thereof creates a draft and cold air is drawn in past the outlet end of the flue system and thereby preheated before being forced by the propeller and fan to circulate past the hotter surfaces of the furnace.

These and other features of the invention will receive further mention in the course of the following description, in which reference is made to the accompanying drawings. In the drawings—

Figure 1 is a transverse, vertical section through a furnace made in accordance with my invention;

Fig. 2 is a fragmentary view taken on the line 2—2 of Fig. 6, showing the automatic controls provided in connection with the furnace;

55

Figs. 3 and 4 are fragmentary longitudinal sections on the lines 3-3 and 4-4, respectively, of Figure 1;

Figs. 5 and 6 are horizontal sections on the lines 5-5 and 6-6, respectively, of Fig. 3;

Fig. 7 is a fragmentary longitudinal section on the line 7-7 of Fig. 2;

Fig. 8 is an enlarged fragmentary transverse vertical sectional detail taken on the line 8-8 of Fig. 6, and

Fig. 9 is an enlarged fragmentary longitudinal sectional detail on the line 9-9 of Fig. 2.

The same reference numerals are applied to corresponding parts throughout the views.

15 Referring to Figs. 1, 2 and 6-9, the numeral 9 is applied to the fire-box which constitutes the supporting base for the gas-fired radiator, indicated generally by the numeral 10, and provides the combustion chamber 11 and secondary air chamber 12 above and below the burners 13. The latter are elongated, as clearly appears in Fig. 6, and extend substantially the full length of the fire-box, and have an elongated pilot burner or inspirator 14 disposed therebetween. A lower opening 15 in the front wall of the fire-box admits air to the secondary air chamber 12 and primary air to the mixers 16 for the main burners and mixer 17 for the pilot burner. Another opening, which is normally closed by a door 18 hinged 20 on the front wall, affords access to the combustion chamber for the purposes of lighting the furnace. The burners are suitably supported on cross members 19 in spaced relation to one another to permit the proper flow of secondary air 25 upwardly between the burners to support combustion, and baffles 20 are provided at the sides and ends of the fire-box, the inner edges of which also have the proper spaced relation to the burners for good aeration of the ports adjacent the same, whereby to insure good combustion. The gas is supplied to the burners through pipe 22 and the intermediate control mechanism numbered 23-25. 23 is a pressure regulator whose function is obvious. 24 is an automatically operated valve, the opening and closing of which is normally taken care of by means of a thermostat in one of the rooms being heated. 25 is a pilot safety valve in the by-pass line 26 leading to the pilot burner. 27 designates a safety device cooperating with the pilot burner 14, and the heating of which by the pilot burner so long as the latter remains lit controls the valves 24 and 25 by virtue of electrical connection therewith, so that the same are closed in case of extinguishment of the pilot light, and prevent the loss of gas and the possible danger of asphyxiation. The valve shown at 28 is one which is manually operable to shut off the flow of gas to the main burners whenever it is desired to dispense with heating for any given period of time. There is no particular novelty in the structure thus far described, excepting in so far as the form and relationship of the burners 13-14 are concerned. The burner 14 maintains the draft upon the shutting off of the main burners 13, and, by reason of its extending the full length of the main burners, serves to insure immediate lighting of the main burners the full length thereof when they are turned on.

70 The radiator 10 has two banks of substantially vertically disposed flues 30 communicating at their lower ends with the top of the combustion chamber 11 and at their upper ends with the bottom of a header manifold or mixing chamber 31. In most gas-fired furnaces the products of combustion enter a chamber similar to the chamber

31 but are discharged directly from this chamber to the smokestack, thereby cutting down the efficiency of the furnace considerably, because it is impossible in such a short travel of the products of combustion to bring about much of a heat exchange between the products and the air circulated past the flues. According to my invention, I provide a more elaborate flue system to the end that the products have ample opportunity to transfer the heat to the air and the products 10 escape up the smokestack at a much lower temperature than is otherwise the case.

15 I provide one bank of flues 32 reaching laterally from the upper end of the header 31, downwardly at an acute angle to the horizontal, and communicating with the side of another header manifold or mixing chamber 33 near the bottom thereof. Still another bank of flues 34 double back above the flues 32 and extend from the top of the header 33 upwardly at an acute angle and 20 communicate with the side of an outlet manifold 35 at the bottom of the latter. The manifolds 31, 33 and 35 extend fore and aft lengthwise of the furnace casing 36, the manifolds 31 and 33 being housed entirely within the casing, 25 but the manifold 35 reaching through the front and back walls so as to permit connection at either end with a conduit 37 leading to the smokestack. The manifolds 31 and 33 constitute intermediate mixing chambers. Thus, the products 30 discharging into the first chamber 31 from the two banks of flues 30 are given an opportunity to mix before delivery to the flues 32. That makes for delivery of the products under the same pressure to all of the flues 32 and at substantially the same temperature. The rate of flow of the products will, therefore, be the same throughout the bank of flues 32. A baffle 38 is 35 preferably provided in the chamber 31 to cause good mixture of the products from the two banks 40 of flues 30 and equalize the distribution of products from the chamber 31 to the flues 32 to insure heating the latter all to about the same degree. With all of the flues 32 heated alike, it is 45 obvious that the efficiency of the heat exchange with the air coming in contact with these flues is bound to be higher than would otherwise be the case. The products discharged from the flues 32 into the chamber 33 are given another opportunity of mixing before they are passed 50 through the flues 34 to the outlet manifold 35, and this accounts in like manner for the even heating of all of the flues in that bank and accordingly a higher efficiency of heat exchange.

55 The flues 32 and 34, it will be observed, slope downwardly toward the manifold 33. This sloping of the flues 32 is primarily with a view to making the products take a tortuous course to insure better heat exchange with the air circulated past 60 the flue system. However, this sloping of the flues 32 and 34 has another advantage, and that is, that any condensation on the walls of these flues will trickle downwardly into the manifold 33. I have formed the bottom 39 of the manifold 33 as a trough sloping toward a drain pipe 40 at one end thereof so as to conduct the moisture to the sewer or other waste receiver. The drainage of the condensation minimizes the rusting of the flues, manifolds, conduits and other metal parts with which moisture-laden products 70 would otherwise come in contact. The fact that the products are on a downward course when they enter the manifold 33 and are forced to reverse 75

their direction of flow in order to enter the flues 34, increases the tendency for moisture to be deposited in the trough 39. The manifold 33 is disposed directly alongside the side wall 41 of the casing 36, and an opening 42 is provided in said wall affording access directly to the inside of the manifold and to all of the flues 32 and 34 communicating therewith. The wall 41 is used as a support for the manifold 33 and the system 10 of flues communicating therewith, as by suitably fastening the flange 43 provided on the manifold to the inside of the wall 41. A cover plate 44 fastened on the outside of the wall 41 for easy removal serves to close the opening 42 and form 15 that side of the manifold 33. The inside of the plate 44 may be and preferably is covered with some suitable heat insulation material faced by a plate of stainless steel or other rust-resistant material, whereby to minimize heat loss 20 through the wall of the furnace at this point. Such insulation has not been shown as a matter of convenience, and it will also be understood that it is only for the sake of convenience that the other walls of the casing 36 are not shown 25 insulated. All walls will be suitably insulated somewhat along the lines disclosed in the co-pending application of Stanley H. Hobson, Serial No. 334,553 filed August 9, 1929, or in any other suitable or preferred manner. The removal of 30 the cover plate 44 enables one to reach all of the flues 32 and 34 for cleaning from the outside of the casing. The flues 30 are accessible through the door 18 and an opening 45 in the front wall of the casing for which a door may or may not be 35 provided, as desired. It is, of course, obvious that the cleaner the flues are kept, the more efficient will be the heat exchange with the air circulated past the flue system. It is for that reason that I have arranged for such convenient 40 access to the flues.

The radiator 10 is set approximately in the middle of the casing 36 and forms part of a partition wall separating the inlet chamber 46 for incoming cold air from the outlet chamber 47 45 for outgoing warm air. Thus, a plate 48 reaching the full length of the casing cooperates with the manifold 31 to form part of this wall. Another plate 49, also reaching the full length of the casing from the manifold 31 downwardly to the 50 fire-box 9, forms another part of this wall. Still another plate 50, reaching substantially the full height of the fire-box and beyond both ends thereof, cooperates with vertically disposed strips 51 at the front and back walls of the casing to 55 complete the lower portion of the partition wall, in addition to forming one side wall of an air jacket 52 for the fire-box 9, as will soon appear. The plate 49 has a circular opening provided therein at the approximate center thereof defined 60 by an annular shroud 53. An annulus 54 surrounds and reinforces the shroud 53. The shroud 53 is provided for an air screw propeller 55 disposed centrally with respect to it and preferably slightly forward with respect to the plane of the 65 back thereof, as best appears in Figs. 1 and 5, such location of the propeller being important from the standpoint of bringing about the proper cooperation of the shroud with the tips of the blades of the propeller, with relation to which 70 the shroud makes an oblique angle. The propeller 55 is carried on the end of a shaft 56 received in bearings 57 provided on the top of the frame 58. The bearings 57 may be of a type which, when once packed with lubricant, will not 75 require attention more than once a year or so,

but I have shown piping 57' extended to these bearings from the side wall 41 to permit supplying oil or grease to these bearings from the outside of the furnace casing to make it unnecessary for one to open the casing to take care of this servicing of the furnace. The frame 58 is mounted on the floor alongside the radiator 10 in the inlet chamber 46 and preferably has sound and vibration-deadening material interposed in the fastenings therefor, which are indicated generally by the numeral 59. An electric motor 60, which also is preferably resiliently mounted on the floor behind the frame 58, as at 61, has a small pulley 62 on the armature shaft thereof in connection with which a belt 63 is used to 15 transmit drive to the propeller through another pulley 64 mounted on the propeller shaft. The pulley 64 is somewhat larger than the pulley 62 to provide for the desired speed reduction between the motor and the propeller. I prefer to 20 use an air screw propeller like the one shown at 55 instead of an ordinary rotary fan because of the established fact that a propeller of this kind is capable of moving a much larger volume of air 25 and still require less power consumption. The operation of air screw propellers is so generally known that it is unnecessary to go to any further length than to state that resistance of the air tending to retard the rotation of such a propeller results in a reaction which accounts for the sucking 30 of a large amount of air into it, and that ordinary rotary fans, not of the air screw type, do not possess that property. The shroud 53 cooperates with the tips of the blades of the propeller so as to prevent a flow of air from the 35 working face around the tips of the blades into the partial vacuum on the other side. The shroud, therefore, enables the propeller to move still more air, by avoiding the losses referred to. It should, therefore, be clear that since I have 40 provided the combination of the most efficient air mover, namely, an air screw propeller, with a shroud to increase its efficiency, the circulation 45 of the desired amount of air through the furnace casing is definitely assured.

In the operation of the propeller, cold air is drawn in through a suitable number of cold air ducts 65 communicating with the top of the inlet chamber 46 and air is propelled from the working face of the propeller through the opening defined by the shroud 53 past the flues 30 into the outlet chamber 47 from whence the air is discharged through a suitable number of warm air ducts 66, which, of course, lead to the rooms to be heated. It is, of course, clear that the cold 50 air immediately after entry into the inlet chamber 46 encounters the outlet manifold 35 and the flues 34 leading thereto. The surfaces of these parts are naturally not at as high a temperature as the surfaces of other parts of the flue system 60 not as remote with reference to the fire-box, but there is, nevertheless, sufficient heat for the cold air entering and coming in contact therewith to have the temperature thereof raised appreciably. The air thus partially heated next comes into 65 contact with the flues 32, which, of course, are at a higher temperature than the flues 34 and outlet manifold 35, so that the air derives further warmth by such contact. Then, finally, the air is circulated past the flues 30, which, of course, 70 are at a much higher temperature than the flues 32, and it is here that the air, preheated, as it were, by contact with the other portions of the flue system, is given its final and principal heating before discharge through the ducts 66. The 75

counterflow of the air to be heated with respect to the products of combustion, as just described, has been demonstrated by test to give the highest obtainable efficiency, much higher than is obtained with furnaces where the products and the air to be heated take the same general direction of flow.

Attention is now called to the fact that I have provided the flues 30 as well as the flues 32 and 34 of streamline cross-section. This is of advantage in three ways—first of all, parts having such form have less head resistance in any air current, so that the flues so formed impose less resistance to the circulation of the air past the same, as will be readily understood by those versed in aeronautics. In a forced draft or hot blast furnace particularly, it is obvious that anything which tends toward less obstruction to the flow is highly beneficial. Secondly, flues of this cross-section do not give rise to dead air spaces to the windward side of the flues, but allow the air flowing past the same to completely envelop and have more intimate contact with the entire surface, which, of course, makes for more efficient heat exchange. Thirdly, the flattening of the flues to the streamline cross-section means a spreading out of the products of combustion into thin streams, thus allowing the walls of the tubes to pick up the heat from the products with facility and give it off to the air coming in contact with the outside of these walls. All of these advantages are not merely theoretical but actual test has shown a stepping up in efficiency approximately 50% over what was obtained with other gas-fired furnaces. That is to say, instead of an efficiency of 60% or even less secured with other gas-fired furnaces, regarded as reasonably efficient, a furnace made in accordance with my invention has shown an efficiency of 90% or better. In passing, it will be observed that the outlet manifold 35 has also been formed of streamline cross-section with the same objects in view as discussed above in regard to the flues. It will also be seen that the flues 30 of the one bank are disposed in staggered relation to the flues of the other bank, as appears in Fig. 5. This is for the purpose of exposing the flues remote from the propeller in the air stream instead of leaving them in the slip stream of the flues in the other bank. In passing, attention may also be called to the somewhat related feature of the special curvature of the bottom wall 67 of the outlet chamber 47, the purpose of which is to deflect the air stream upwardly toward the top of the outlet chamber 47 with minimum loss in velocity. I have found that by giving the wall 67 a parabolic curvature there is less resistance to the bending of the air stream and the operation is not attended with objectionable noise such as must otherwise be tolerated. The wall 67 may be and preferably is insulated to minimize heat loss. The wall 67 is suitably provided with a water trough 68 set in an opening 69 therein, and a pipe 70 extends lengthwise in this trough and has a suitable number of holes in the bottom wall thereof for the delivery of water at a rate determined by the adjustment of a valve 71 provided on the outside of the furnace casing (see Fig. 6). The trough 68 is purposely placed far enough toward the upper end of the wall 67 in spaced relation to what I call a ship's funnel 72, the purpose of which is hereinafter described, so that when the valve 71 is opened wide enough there will be an

overflow of water from the trough and the water will form a thin film or sheet on the wall 67 between the trough 68 and funnel 72, whereby to provide for effective humidification of the air. It is obvious that since the air is deflected by contact with the wall 67, and the wall is covered with a thin film of water as just stated, the conditions are ideal for good humidification. The valve 71 will, of course, be regulated so that there will not be an excessive flow. Automatic devices 10 are provided to stop the electric motor 60 and close the valve 24 so as to shut off the gas to the burners 13 simultaneously with the stopping of the motor, and it will be evident that an automatic shut-off valve could also be provided in connection with the pipe 70 to stop the delivery of water when the furnace is automatically shut off.

The jacket 52 for the fire-box 9 received brief mention above. This jacket completely encloses the four sides of the fire-box, as best appears in Figs. 1 and 6. The plate 50, as indicated above, forms one side wall; another plate 73 forms the opposite side wall, and there are end walls at 74 and 75, as appears in Fig. 6, the wall 75 terminating just above the door 18, as shown in Fig. 7. Now, an opening 76 is provided in the wall 50 near the bottom of the jacket, and another opening 77 is provided in the opposite wall 73 at the top of the jacket, and air is arranged to be supplied through the opening 76 for circulation through the jacket about the four sides of the fire-box from bottom to top to be heated by contact with these hot walls, and the air so heated is arranged to be discharged through the opening 77 into the outlet chamber 47. The opening 76 is elongated almost to the full length of the fire-box so that the air admitted to the jacket 52 through this opening will come in contact with the fire-box the full length thereof. I provide a fan 78 on the armature shaft of the motor 60 in front of the pulley 62 to provide forced circulation of air through the jacket 52. A duct 79, which is generally funnel-shaped, has the small end thereof formed to provide a circular air intake opening in which the fan 78 is received as in a shroud, and the same is flared toward the outlet end which is formed to an elongated rectangular shape and fits over flanges 80 defining the opening 76. The curvature of the top and bottom walls of this duct as shown in Figure 1 tends to deflect the air so that it is discharged upwardly through the opening 76 into the jacket 52 in the general direction of the opening 77 at the opposite side of the jacket. Warm air is therefore delivered at an appreciable velocity through the opening 77 which extends preferably the full length of the wall 73. Another duct 81 is provided to direct the warm air discharged from the opening 77 upwardly through the opening 82 of the ship's funnel 72. The duct 79 is, of course, supported on one end on the flanges 80 and may be supported at the other end in any suitable manner, as for example, by means of cross members 83 on the frame 58. The duct 81 is fastened to the walls 67 and 73, as indicated. In operation, the fan 78 will be driven at a higher speed than the propeller 55 due to its being mounted directly on the armature shaft. The suction created in the operation of this fan further insures good intake of cold air through the ducts 65 and, of course, the air delivered through the duct 79 to the jacket 52 is preheated by reason of its having had contact with the flues 32 and 34 and the outlet manifold 35. Consequent-

ly, there is no sudden stepping up in temperature of this air by contact with the side walls of the fire-box. In other words, the counter-flow principle of operation applies to this portion of the furnace as well as to the other. The warm air discharge through the duct 81 into the outlet chamber 47 goes with the warm air circulated by the propeller 55 and is, of course, discharged with it through the warm air ducts 66. Owing to the fact that such a small fan is used and it is out of the question to streamline the fire-box and there is, consequently, more or less obstruction to the flow of air through the jacket, I prefer to provide the funnel 72 for the purpose of accelerating the flow through the jacket 52. In other words, the strong draft created by the propeller 55 over the back of the funnel 72 creates sufficient reduction in pressure at the opening 82 to accelerate the flow of air through the jacket 52.

It is believed the foregoing description conveys a clear understanding of all of the objects and advantages of my invention. The invention is susceptible of a considerable amount of modification without sacrificing the more important advantages that have been outlined. The appended claims have, therefore, been drawn to embrace all changes coming within the spirit and scope of the invention.

I claim:

1. In a furnace, the combination of a fuel burner, an elongated fire-box therefor, an elongated manifold above the latter, substantially vertically disposed primary flues establishing communication between the fire-box and manifold to conduct products of combustion from the former to the latter, a casing enclosing the aforesaid elements, the inside of the casing being divided into an outlet chamber on one side of said flues and an inlet chamber on the other side thereof, one or more openings provided in said casing for admitting cold air to the inlet chamber in said casing, another manifold in the inlet chamber, secondary flues establishing communication between the two manifolds for conducting the products of combustion from the first to the second manifold, an air propeller disposed between the two sets of flues and in close proximity to the primary flues, and one or more openings provided in said casing for discharging warm air from the outlet chamber in said casing, the said propeller being adapted in the operation thereof to cause a reduction in pressure in the inlet chamber, whereby to draw in cold air, and create pressure in the outlet chamber whereby to discharge warm air under pressure.

2. In a furnace, the combination of a fuel burner, an elongated fire-box therefor, an elongated manifold above the latter, substantially vertically disposed primary flues establishing communication between the fire-box and manifold to conduct products of combustion from the former to the latter, a casing enclosing the aforesaid elements, the inside of the casing being divided into an outlet chamber on one side of said flues and an inlet chamber on the other side thereof, one or more openings provided in said casing for admitting cold air to the inlet chamber in said casing, a second manifold in the inlet chamber, secondary flues connecting the first manifold with the second, a third manifold in the inlet chamber, other flues connecting the second manifold with the third, these flues being disposed between the inlet openings and the previously mentioned flues, the products of com-

bustion being arranged to be conducted in one direction from the first manifold through the secondary flues to the second manifold and from thence in a different direction through the other flues to the third manifold for discharge from the furnace, an air propeller disposed between the primary and secondary flues and in close proximity to the primary flues, and one or more openings provided in said casing for discharging warm air from the outlet chamber in said casing, the said propeller being adapted in the operation thereof to cause a reduction in pressure in the inlet chamber, whereby to draw in cold air, and create pressure in the outlet chamber whereby to discharge warm air under pressure.

3. In a furnace, the combination of a casing providing an inlet chamber and an outlet chamber, a radiator in said casing comprising a fire-box, a flue system embodying a first and hottest bank of flues communicating directly therewith and one or more succeeding banks of flues communicating with said hottest bank, and an outlet manifold communicating with the bank of flues most remote from the fire-box for discharge of the products of combustion from the furnace, one or more outlet openings for said casing for the discharge of warm air from the outlet chamber, an air propeller disposed in the one chamber in close proximity to the first bank of hottest flues, whereby to secure direct impingement of air at highest velocity upon said flues for an efficient heat exchanging scrubbing action, said propeller serving to create a reduction in pressure in the inlet chamber and create pressure in the outlet chamber for the discharge of warm air under pressure, and one or more inlet openings for said casing to admit cold air to the inlet chamber when the reduction in pressure is created therein, said inlet openings being so located on said casing with relation to the flue system for the counter-flow of air with relation to the general direction of flow of the products of combustion in said system.

4. A gas furnace comprising an elongated fire-box, an elongated manifold above the same, flues extending upwardly from the top of the fire-box and connecting the latter with the manifold, a second manifold below the level of the first, flues extending laterally from the side of the first manifold with downward inclination toward the second manifold and communicating with the side of the latter at or near the bottom thereof whereby to provide a trap for condensation in the second manifold, means for conducting the condensation from said manifold, a third manifold above the level of the second manifold and at a point between the first two manifolds, and flues communicating with the second manifold at or near the top thereof and extending laterally therefrom with upward inclination and in the reverse direction to the second flues toward the third manifold to conduct products of combustion to the latter, the products being conducted from the first manifold downwardly toward the second manifold in one direction and being conducted from the second manifold upwardly toward the third manifold in the opposite direction whereby to insure more complete separation of the moisture from the products of combustion in the second manifold.

5. In a hot blast type furnace, the combination of a casing having one or more cold air inlet openings and one or more warm air outlet openings, a heat radiator in said casing between said

- inlets and outlets, the same comprising a fire-box, a header manifold for discharging products of combustion from the furnace, and flues for conducting products from the fire-box to the header manifold, means whereby the flues are encased, means whereby the fire-box is separately encased, air moving means for causing air to be circulated under pressure past the flues and past the fire-box to abstract heat therefrom, the air after such passage being conducted toward the warm air outlets for discharge from the casing, said air moving means comprising a propeller or the like cooperating with the means encasing the flues, and a separate fan or the like cooperating with the means encasing the fire-box, and means for driving said propeller and fan simultaneously.
6. In a hot blast type furnace, the combination of a casing having one or more cold air inlet openings and one or more warm air outlet openings, a heat radiator in said casing between said inlets and outlets, the same comprising a fire-box, a header manifold for discharging products of combustion from the furnace, and flues for conducting products from the fire-box to the header manifold, means whereby the flues are encased, means whereby the fire-box is separately encased, air moving means for causing air to be circulated under pressure past the flues and past the fire-box to abstract heat therefrom, the air after such passage being conducted toward the warm air outlets for discharge from the casing, said air moving means comprising a propeller or the like cooperating with the means encasing the flues, and a separate fan or the like cooperating with the means encasing the fire-box, and a shaft for driving the fan and propeller, the fan being mounted on the shaft and the latter having a reduction drive connection with the propeller.
7. A gas furnace comprising an elongated fire-box having one or more burners therein, an elongated manifold above the fire-box, flues extending upwardly from the fire-box and communicating with the bottom of the manifold, one or more other elongated manifolds, flues communicating with the side of the first manifold at or near the top thereof and extending therefrom for communication with one of the other manifolds, the manifold most remote from the fire-box having communication with an outlet for discharge of the products of combustion from the furnace, and a baffle in at least the first manifold disposed transversely with respect to the first mentioned flues whereby to equalize distribution of the products of combustion from the first manifold to the second flues.
8. In a hot blast type furnace, the combination of a casing, a heat radiator disposed in an intermediate position in said casing dividing the same substantially vertically into an inlet chamber on one side thereof and an outlet chamber on the other side, the said heat radiator comprising a fire-box, flues extending upwardly therefrom to conduct products of combustion therethrough for heat transfer to the air circulated past the outside thereof, and a manifold communicating with the upper ends of said flues for discharge of the products from the furnace, a power operated propeller or the like disposed in the inlet chamber in juxtaposition to the flues and arranged to throw air substantially horizontally from the inlet chamber past the flues into the outlet chamber so as to be heated by contact with the flues, one or more cold air inlet openings for

the inlet chamber, one or more warm air outlet openings in the upper portion of the casing communicating with the outlet chamber, a deflecting wall in the outlet chamber for deflecting the air after passing the flues from a substantially horizontal direction of flow upwardly toward the outlets, a power operated fan or the like disposed in the inlet chamber adjacent the fire-box and arranged to force air to circulate about the fire-box from the inlet chamber in the direction of the outlet chamber, and means for directing the air after passing the fire-box upwardly through an opening provided in the deflector whereby to discharge it with the other warm air in the direction of the warm air outlets.

9. In a hot blast type furnace, the combination of a casing, a heat radiator disposed in an intermediate position in said casing dividing the same substantially vertically into an inlet chamber on one side thereof and an outlet chamber on the other side, the said heat radiator comprising a fire-box, flues extending upwardly therefrom to conduct products of combustion therethrough for heat transfer to the air circulated past the outside thereof, and a manifold communicating with the upper ends of said flues for discharge of the products from the furnace, a power operated propeller or the like disposed in the inlet chamber in juxtaposition to the flues and arranged to throw air substantially horizontally from the inlet chamber past the flues into the outlet chamber so as to be heated by contact with the flues, one or more cold air inlet openings for the inlet chamber, one or more warm air outlet openings for the outlet chamber, and an air jacket for the fire-box, the same having a cold air inlet opening in the lower portion thereof on one side communicating with the inlet chamber, and a warm air outlet opening in the upper portion thereof at the opposite side, the warm air outlet opening having communication with the outlet chamber for the discharge of the air heated by the firebox to the warm air outlets.

10. A furnace as set forth in claim 9 wherein the warm air outlets are provided in the upper portion of the casing, the furnace including a deflecting wall impinged by the air after passing the flues and arranged to deflect the air upwardly toward the warm air outlets, a duct establishing communication between the warm air outlet of the air jacket and an opening provided in said deflector wall, and a baffle over the last mentioned opening for deflecting the air coming from the flues upwardly away from said opening, whereby to produce a ship's funnel effect to accelerate the circulation of air through the air jacket.

11. In a hot blast type furnace, the combination of a casing, a heat radiator disposed in an intermediate position in said casing dividing the same substantially vertically into an inlet chamber on one side thereof and an outlet chamber on the other side, the said heat radiator comprising a fire-box, flues extending upwardly therefrom to conduct products of combustion therethrough for heat transfer to the air circulated past the outside thereof, and a manifold communicating with the upper ends of said flues for discharge of the products from the furnace, a power operated propeller or the like disposed in the inlet chamber in juxtaposition to the flues and arranged to throw air substantially horizontally from the inlet chamber past the flues

into the outlet chamber so as to be heated by contact with the flues, one or more cold air inlet openings communicating with the inlet chamber, the said propeller when operated creating a reduction in pressure in said inlet chamber to cause air to be drawn through said inlets toward the propeller, secondary flues communicating with the manifold and disposed between the inlets and the propeller to provide an additional pass of the products of combustion in the inlet chamber for contact of the incoming cold air whereby to preheat the same before contact with the first flues, one or more warm air outlet openings in the upper portion of the casing communicating with the outlet chamber, a deflecting wall in the outlet chamber for deflecting the air after passing the flues from a substantially horizontal direction of flow upwardly toward the outlets, an air jacket for the fire-box, a separate fan or the like arranged to produce forced circulation of air through said jacket from the inlet chamber toward the outlet chamber, and means for directing the air leaving the jacket upwardly toward the warm air outlets for discharge along with the other warm air.

12. In a furnace, the combination of a fire-box, a manifold, primary flues establishing direct communication between the fire-box and manifold to conduct products of combustion from the former to the latter, an enclosing casing for the aforesaid elements, the same being provided with one or more inlet and outlet openings on opposite sides of the flues for the admission of cold air and the discharge of warm air from the casing, off-take flues communicating with the manifold and disposed between the intake openings and the first mentioned primary flues, and an air propeller disposed between the primary flues and the off-take flues in close proximity to the primary flues whereby to secure direct impingement of air at highest velocity upon the primary flues for a scrubbing action and effectively transfer heat to the air from the products of combustion, and whereby at the same time to secure circulation of air at lower velocity about the off-take flues for preliminary heat transfer therefrom.

13. In a furnace, the combination of a casing, a heat radiator disposed therein between an inlet chamber and an outlet chamber in the casing, the said heat radiator comprising a fire-box and heat radiating members communicating therewith for conducting products of combustion therefrom, a power-operated propeller or the like disposed in the inlet chamber in juxtaposition to the heat radiating members and arranged to throw air past the same into the outlet chamber so as to be heated by contact with said members, one or more cold air inlet openings for the inlet chamber, one or more warm air outlet openings in the upper portion of the casing communicating with the outlet chamber, a deflector in the outlet chamber for deflecting the air from the heat radiating members upwardly toward the outlets, means whereby air is circulated from the inlet chamber about the fire-box to abstract heat therefrom, and means for conducting the air from the last mentioned means for discharge jointly with the other warm air through the warm air outlets.

14. In a hot blast type furnace, the combination of a casing, a heat radiator disposed in an intermediate position in said casing between an inlet chamber on one side thereof and an outlet chamber on the other side, the said heat radiator comprising a fire-box, flues extending upwardly therefrom to conduct products of combustion therethrough for heat transfer to the air circulated past the outside thereof, and a manifold communicating with the upper ends of said flues for discharge of the products from the furnace, a power operated propeller or the like disposed in the inlet chamber in juxtaposition to the flues and arranged to throw air substantially horizontally from the inlet chamber past the flues into the outlet chamber so as to be heated by contact with the flues, one or more cold air inlet openings for the inlet chamber, one or more warm air outlet openings for the outlet chamber, an air jacket for the fire-box, the same having a cold air inlet opening in the lower portion thereof on one side communicating with the inlet chamber, and a warm air outlet opening in the upper portion thereof at the opposite side, the warm air outlet opening having communication with the outlet chamber for the discharge of the air heated by the fire-box to the warm air outlets, and a power operated fan or the like in the cold air inlet opening in said air jacket.

15. In a hot blast type furnace, the combination of a casing, a heat radiator disposed in an intermediate position in said casing between an inlet chamber on one side thereof and an outlet chamber on the other side, the said heat radiator comprising a fire-box, flues extending upwardly therefrom to conduct products of combustion therethrough for heat transfer to the air circulated past the outside thereof, and a manifold communicating with the upper ends of said flues for discharge of the products from the furnace, a power operated propeller or the like disposed in the inlet chamber in juxtaposition to the flues and arranged to throw air substantially horizontally from the inlet chamber past the flues into the outlet chamber so as to be heated by contact with the flues, one or more cold air inlet openings for the inlet chamber, one or more warm air outlet openings for the outlet chamber, and an air jacket for the fire-box having communication on one side with the inlet chamber and on the other side with the outlet chamber for the circulation of air to be heated about the fire-box, said jacket having communication with the inlet chamber in such relation to the direction of air flow therein whereby circulation of air about the jacket is accelerated in the operation of the propeller.

16. A furnace as set forth in claim 9 wherein the warm air outlets are provided in the upper portion of the casing, the furnace including a deflecting wall impinged by the air after passing the flues and arranged to deflect the air upwardly toward the warm air outlets, a duct establishing communication between the warm air outlet of the air jacket and an opening provided in said deflecting wall, a baffle over the last mentioned opening for deflecting the air coming from the flues upwardly away from said opening, whereby to produce a ship's funnel effect to accelerate the circulation of air through the air jacket, and a power operated fan or the like in the cold air inlet opening of the air jacket to further insure good circulation of air through said jacket.

17. In a furnace, the combination of a fire-box, a manifold, flues establishing communication between the fire-box and manifold to conduct products of combustion from the former to the latter, an enclosing casing for the aforesaid elements, the same being provided with one or more inlet and outlet openings on opposite sides of the flues for the admission of cold air and the discharge of warm air from the casing, a deflector wall in the outlet chamber for deflecting the air from the flues upwardly toward the warm air outlets, means whereby air is circulated from the inlet chamber about the fire-box to abstract heat therefrom, and means for conducting the air from the last mentioned means for discharge jointly with the other warm air through the warm air outlets.

- flues for the admission of cold air and the discharge of warm air from the casing, offtake flues communicating with the manifold and disposed between the intake openings and the first mentioned flues, and an air propeller disposed between the first flues and the offtake flues in close proximity to the first flues whereby to secure direct impingement of air at high velocity upon the first flues for a scrubbing action and effectively transfer heat to the air from the products of combustion, and whereby at the same time to secure circulation of air at lower velocity about the offtake flues for preliminary heat transfer therefrom, all of said flues being of flattened form and substantially streamline cross-section and disposed with the major axis of such section substantially parallel with the direction of air flow relative thereto, whereby to minimize restriction to air flow and insure better scrubbing action of the air on the surface of the flues.
18. In a hot blast type furnace, the combination of a casing having an inlet chamber with one or more cold air inlet openings and an outlet chamber with one or more warm air outlet openings, a heat radiator in said casing between said inlets and outlets, the same comprising a fire-box, a header manifold for discharging products of combustion from the furnace, and flues for conducting products from the fire-box to the manifold, separate and independent passages in said casing for conducting air from the inlet chamber to the outlet chamber, for heat absorbing contact with the flues on the one hand, and with the fire-box on the other hand, air moving means for simultaneously causing air to be circulated under pressure through said passages past the flues and past the fire-box to abstract heat therefrom, the warm air outlets in the outlet chamber being provided in the upper portion thereof, a deflecting wall impinged by the air circulated past the flues and arranged to deflect the air upwardly toward the warm air outlets, said deflector wall having an opening provided therein communicating with the passage conducting the air past the fire-box, and a baffle over the last mentioned opening for deflecting the air coming from the flues upwardly away from said opening whereby to produce a ship's funnel effect to accelerate the circulation of air past the fire-box.
19. In a hot blast type furnace, the combination of a fire-box, a manifold, primary flues establishing direct communication between the fire-box and manifold to conduct products of combustion from the former to the latter, an inlet chamber on one side of the flues, an outlet chamber on the other side of the flues, the inlet chamber having one or more cold air inlets and the outlet chamber having one or more warm air outlets, means for conducting the products of combustion from the manifold for discharge from the furnace, said means being disposed in the intake chamber in the path of air travel therethrough whereby to transfer residual heat from the products of combustion to the air for pre-heating, and an air propeller disposed downstream with respect to said means in close proximity to the first mentioned primary flues, whereby to cause direct impingement of the pre-heated air at high velocity upon the primary flues for the principal heat exchange, and whereby at the same time to secure circulation of air at lower velocity past the preheating means, the operation of said propeller resulting in increase in pressure in the outlet chamber for induced discharge of warm air through the warm air outlets.
20. In a hot blast type furnace, the combination of a fire-box, a manifold, flues establishing communication between the fire-box and manifold to conduct products of combustion from the former to the latter, an inlet chamber on one side of the flues, an outlet chamber on the other side of the flues, the inlet chamber having one or more cold air inlets and the outlet chamber having one or more warm air outlets, means for conducting the products of combustion from the manifold for discharge from the furnace, said means being disposed in the intake chamber in the path of air travel therethrough whereby to transfer residual heat from the products of combustion to the air for preheating, and an air propeller disposed downstream with respect to said means in close proximity to the first mentioned flues, whereby to cause direct impingement of the preheated air at high velocity upon the flues for the principal heat exchange, and whereby at the same time to secure circulation of air at lower velocity past the preheating means, the operation of said propeller resulting in increase in pressure in the outlet chamber for induced discharge of warm air through the warm air outlets.
21. In a furnace, the combination of a fuel burner, an elongated fire-box therefor, an elongated manifold above the latter, substantially vertically disposed flues establishing communication between the fire-box and manifold to conduct products of combustion from the former to the latter, a casing enclosing the aforesaid elements, a vertical wall on one side of the flues dividing the casing into an inlet and an outlet chamber, said wall having an opening therein, and an air propeller in the inlet chamber registering with said opening and disposed in close proximity to the flues, there being one or more openings provided in said casing for admitting cold air to the inlet chamber in said casing, and one or more openings provided in said casing for discharging warm air from the outlet chamber in said casing, offtake flues connected to said manifold and traversing the inlet chamber in the path of cold air passing through said chamber, whereby to transfer heat thereto, the said propeller being adapted in the operation thereof to cause air to impinge directly upon the first flues for the principal heat transfer, and at the same time cause a reduction in pressure in the inlet chamber, whereby to draw in cold air past the offtake flues, and create pressure in the outlet chamber whereby to discharge warm air under pressure.
22. In a furnace, the combination of a fire-box, a manifold, flues establishing communication between the fire-box and manifold to conduct products of combustion from the former to the latter, an enclosing casing for the aforesaid elements, the same being provided with one or more inlet and outlet openings on opposite sides of the flues for the admission of cold air and the discharge of warm air from the casing, offtake flues communicating with the manifold and disposed between the intake openings and the first men-

tioned flues, and an air propeller disposed between the first flues and the offtake flues in close proximity to the first flues whereby to secure direct impingement of air at high velocity upon the first flues for a scrubbing action and effectively transfer heat to the air from the products of combustion, and whereby at the same time to secure circulation of air at lower velocity about the offtake flues for preliminary heat

transfer therefrom, at least the first mentioned flues being of flattened form and substantially streamline cross-section and disposed with the major axis of such section substantially parallel with the direction of air flow relative thereto, whereby to minimize restriction to air flow and insure better scrubbing action of the air on the surface of the flues. 5

JAMES M. FUNK.
